INVENTOR

Louie A. Branson,

By Albert M. Moore,
Her ATTORNEY.

UNITED STATES PATENT OFFICE.

LOUISE A. BRANSON, OF LOWELL, MASSACHUSETTS.

ASH-SIFTER.

SPECIFICATION forming part of Letters Patent No. 678,934, dated July 23, 1901.

Application filed November 3, 1899. Serial No. 735,726. (No model.)

To all whom it may concern:

Be it known that I, LOUISE A. BRANSON, a citizen of the United States, and a resident of Lowell, in the county of Middlesex and State 5 of Massachusetts, have invented certain new and useful Improvements in Ash-Sifters, of which the following is a specification.

My invention relates to ash-sifters, and comprises a scoop adapted to be thrust into the 10 ash-pit of a stove or furnace to transfer ashes from said pit to the sifter, a suitable door, normally closing said scoop, a discharge end, closed by a gate or door, a screen, a flexible 15 hollow body of dust-proof incombustible material connecting said scoop and discharge end to said screen and other parts hereinafter described, the whole constituting a portable sifter which may be used in a furnished room without scattering ashes and which may 20 be folded in small space when not in use or for transportation.

My invention consists in the devices and the combinations hereinafter described and claimed.

In the accompanying drawings, Figure 1 is a right side elevation of a sifter embodying my invention, the scoop being closed, and Fig. 2 a plan of the same, parts of the hollow body being broken out in Figs. 1 and 2 to 25 economize space in the drawings; Fig. 3, a central longitudinal section on the line 3 3 in Fig. 2 except that the scoop is open in Fig. 3 and closed in Fig. 2; Fig. 4, a front elevation of the scoop end of the sifter; Fig. 5, a vertical longitudinal section on the line 5 5 in Fig. 6 of the screen and adjacent parts; Fig. 6, a vertical transverse section on the line 6 6 in Fig. 1; Fig. 7, a central longitudinal section on the line 7 7 in Fig. 2.

Thesifter herein described consists of three 40 parts or sections, the scoop-section A, the screen-section B, and the discharge-section C, these all being made of comparatively rigid fireproof material, preferably of sheet metal, 45 the screen-section being connected to the other section by hollow or tubular bodies D D' of flexible dust-proof and fireproof material, preferably asbestos cloth. The sections A, B, and C and the hollow connections D D' 50 are preferably rectangular in cross-section.

The scoop A consists of a box having an inclined front end a, normally closed by a door

or flap a', the upper end of which turns on a rod a², supported in ears a³ a⁴ or upward extensions of the sides a⁵ a⁶, a spring a⁷ (represented as a spiral spring surrounding said rod a² and pressing against the top of the scoop or box A and the front of said flap) serving to close said flap and to keep the same closed. A hook a⁸, secured on the front of the flap a', may be engaged by another hook a¹⁰, which slides in a loop a⁹, secured on the top of the scoop A to hold said flap open when the scoop is being used to take up the ashes or other material. The hook a⁸ serves 65 as a handle to lift the flap. The rear end of the hook a¹⁰ is provided with a bent-up portion or hook a¹¹, which prevents the shank a¹² or sliding part of said hook a¹⁰ a¹¹ from being removed from the loop a⁹, and also serves as a 70 handle for said hook a¹⁰.

The front or inclined end of the scoop is provided on the inside at the top and sides with a ledge a¹³, on which the flap rests when closed to prevent the escape of dust.

The scoop A is provided with a yoke-shaped handle a¹⁴, formed of a wire bent as shown and having the ends rigidly secured to the sides of said scoop in any convenient manner.

The screen-section B is a suitable frame 80 containing a transversely-arranged sieve or screen b and provided with a suitable handle b', represented as a yoke-shaped wire, the sides of which are arranged to slide in grooves b² b² in the sides of said frame and retained 85 therein by caps b³ b³, which cover said grooves for some distance from the top of said frame. The ends b⁴ b⁴ of the handle b' are bent out to project slightly from the grooves b² b² and are stopped by the caps when said handle is 90 raised to the position shown by dotted lines in Fig. 6.

The handle when not in use occupies the position shown by full lines in said Fig. 6, the middle portion of the handle resting on the 95 screen-frame.

The discharge-section C is a frame containing a sliding gate c, normally closed and opened only to discharge ashes, the rear end (the right end in Figs. 1, 2, and 7) being conveniently contracted, as shown, to form a chute or discharge-pipe c' to enable the ashes to be transferred to a receptacle smaller in section than the body of the discharge-section.

The tubular connections D D' between the scoop and the screen and between the screen and the discharge-section are of any suitable flexible fireproof and dust - proof material, 5 preferably of asbestos cloth. The ends of these tubes D D' are inserted in the frames or sections to which said ends respectively belong and are retained therein by sleeves d d' d² d³, arranged within said ends, and by rivets 10 d⁴, which pass through said frames, sleeves, and ends in an obvious manner.

When the space in the tube D is sufficiently filled with ashes and cinders, the sifter is shaken, the handles being held in the hands 15 for that purpose (both of the doors or gates a' c being previously closed) until the ashes are separated from the coals or cinders, and the ashes are then discharged through the

discharge-section and the coals through the 20 scoop-section.

I claim as my invention—

1. A portable sifter, comprising a scoop, a screen and a flexible tubular connection between said scoop and said screen.

2. A portable sifter, comprising a scoop, a 25 screen, a discharge-section, and flexible tubular connections between said scoop and said screen and between said screen and said discharge-section.

In testimony whereof I have affixed my sig- 30 nature in presence of two witnesses.

LOUISE A. BRANSON.
